UNITED STATES PATENT OFFICE.

BERNARD I. ROCKOFF AND ELIAS ROCKOFF, OF CHICAGO, ILLINOIS.

MULTIPLE LAMP SOCKET.

Application filed June 26, 1919. Serial No. 306,775.

To all whom it may concern:

Be it known that BERNARD I. ROCKOFF and ELIAS ROCKOFF, citizens of the United States, residing at Chicago, in the county 5 of Cook and State of Illinois, have invented a certain new and useful Improvement in Multiple Lamp Sockets, of which the following is a full, clear, concise, and exact description, reference being had to the accompanying drawings, forming a part of 10 this specification.

The invention relates to a combined plug and lamp socket and particularly to that type of these devices in which a multiplicity 15 of lamps or other devices may be connected for use.

The invention has among its various objects the production of a device of this character in which the elements which secure the 20 various portions forming the device together, are arranged so that they contact with each other and produce conductors which lead from the plug end to the various sockets. By the arrangement resorted to 25 and the elements utilized the necessity of producing special devices for these purposes is entirely eliminated, which thus materially reduces the cost of manufacture, without reducing the efficiency of the device.

30 The invention has as an additional object the provision of an arrangement which permits one part thereof to be independently separated from the other, so as to facilitate repairing the device should this 35 at any time be found necessary or desirable.

In other words the plug end may be removed without demanding the separation of the sockets. Also the parts forming the sockets may be separated from the body portion 40 of the device and from each other without interfering with the plug and its elements.

The invention has as a further object the accomplishment of these and other advantages all of which will be more readily 45 understood and explained in detail with reference to the accompanying drawings, in which one embodiment of the invention is illustrated, and in which,—

Fig. 1 is a central section of a lamp socket 50 embodying the invention;

Fig. 2 is a section on line 2—2 of Fig. 1;

Fig. 3 is a section on line 3—3 of Fig. 2; and

Fig. 4 is an end view of one of the lamp 55 sockets.

The construction of the invention as il-

lustrated in the drawings contemplates the use of a body portion 10 which may be of porcelain or other suitable insulating material, the plug portion generally designated 60 11, and the socket portions generally designated 12 and 13.

The portions forming the plug end 11 are held with relation to the body portion 10 by means of the screw threaded conductor 65 14 which passes through the plug and through the body 10, and is provided with the nut 15 which is arranged in a recess 16, this recess being closed by any suitable sealing medium 17. The plug end 11 is 70 composed of the insulating button portion 18 and screw threaded shell 19, and the insulated neck portion 20 which is shown as being separate from the body 10, but may be integral therewith if so desired. The 75 shell 19 is cap-shaped and is provided with an aperture 21 so as not to contact with the member 14 at this point. A conductor 22^a extends from the shell 19 through the neck portion and down into the body portion 10, where it contacts with a conductor which leads to the shells of the sockets 12 and 13. The sockets 12 and 13 include the threaded shells 22 and 23 respectively, which are covered by the internally threaded insulating 80 sleeves 24. The shells 22 and 23 are held with relation to the body 10 by means of the screw threaded members 25 and 26, which pass through the body portion 10 transversely to the conductors 14 and 22^a, 90 and through one wall of the shells 22 and 23, these shells being held with relation to the body portion 10 by means of the enlarged heads of the screw threaded members 25 and 26, and the nuts 27. 95

The wall of the shells 22 and 23 adjacent the body portion 10 is cut away to accommodate the contact elements 28—28 which contact with one terminal of a lamp or other device which is inserted into the 100 socket. It being understood that these contacts 28—28 are also suitably insulated from the shells 22 and 23 in the usual manner.

These contact elements are held with relation to the body portion 10 by means of 105 a threaded member 29 which also has an enlarged head and the nut 30. This member 29 passes through the body portion 10 and is arranged parallel to the members 25 and 26. 110

By referring to Fig. 2 it will be seen that the members 14 and 22^a contact with the

transverse members such as 29 and 25, and that said members 29 and 25 terminate in a connection with the shells 22 and 23 and the contact elements 28-28, respectively.

5 Thus when the plug end 11 is inserted into a socket, current will flow through the members 14 and 29 to the contact elements 28-28, through the lamps in the sockets 12 and 13, to the shells 22 and 23, through the 10 member 25 to the conductor 22^a and thence to the shell 19 arranged upon the plug 11 and out over the line.

Whereas the invention is illustrated as serving two sockets it is apparent that the 15 construction is not limited to this and that the number may be increased. It is further evident that by lengthening the conductors 22^a and 14 that any desired number of vertically arranged sockets may be supplied with 20 current therefrom.

From the foregoing it is also apparent that a simple and effective arrangement is produced in which the members which secure the socket shells and other elements to the 25 body portion 10 provide the conductors which eliminates the necessity of special devices for this purpose, and also the expense of specially designed tools for their manufacture. This naturally materially reduces the cost of manufacture, and results in an extremely simple arrangement having the same efficiency as a more complicated construction.

It is also apparent that the parts producing the plug end may be separated from the 35 sockets without demanding that anything be done to the latter, also that the sockets may be separated from the body portion without demanding that the plug end be interfered 40 with.

Having thus described one embodiment of the invention, it is obvious that changes and modifications may be made without departing from the scope of the appended claims.

45 What we claim and desire to cover by Letters Patent is:

1. In a device of the class described, the combination of a body portion, a plug and a plurality of sockets secured to the body

portion, said plug and sockets having contact making elements, means for securing the contact making elements of the sockets with relation to said body portion, said means including a pair of parallel conducting bolt members, and means for securing the contact making elements of the plug to the body portion, said means including a pair of parallel bolt members which are arranged at an angle to and in electrical contact with the parallel conducting bolt members of the sockets.

2. In a device of the class described the combination of a body portion having a plug and a socket, the plug and socket having contact making elements, bolt members for holding the contact making elements of the plug and socket with relation to the body portion, said plug contact holding bolt members being arranged at an angle to said socket contact holding bolt members and in 70 electrical contact therewith.

3. In a device of the class described, the combination of a body portion, a plug and a plurality of sockets connected thereto, said plug and sockets each having a shell and another contact making element, a pair of parallelly arranged separated conductors leading from the shell and center contact of the plug, a pair of parallelly arranged bolt members providing conductors one of which connects the shells of the sockets together and the other of which connects the center contacts thereof together, the conductors of the plug and sockets being arranged at an angle to and in contact with each other, the conductor which leads from the shell of the plug being in contact with the bolt member which connects the shells of the sockets together, and the conductor which leads from the center contact making element of the plug being in contact with the bolt member which connects the center contact making elements of the sockets together.

In witness whereof, we hereunto subscribe our names this 7th day of June A. D. 1919.

BERNARD I. ROCKOFF
ELIAS ROCKOFF.
